CLAIM

The ornamental design for a wearable cooking timer, as shown and described.

DESCRIPTION

FIG. 1 is a top plan view of a wearable cooking timer according to a first embodiment, showing our new design.

FIG. 2 is a bottom plan view thereof.

FIG. 3 is a right side view thereof.

FIG. 4 is a left side view thereof.

FIG. 5 is a front end view thereof; and,

FIG. 6 is a rear end view thereof.

The broken lines shown in the figures illustrate portions of the wearable cooking timer that form no part of the claimed design.
